APPARATUS FOR PRODUCING HOLLOW
BRICKS CLOSED ON ALL SIDES

Jan Putterlisk, Prague, Czechoslovakia

Application June 12, 1934, Serial No. 730,199½
In Czechoslovakia June 22, 1933

8 Claims. (Cl. 25—17)

The invention relates to a method and device for producing hollow bricks closed on all sides, and in particular to an improved mouth piece which can be fitted to any existing brick making machine with which hollow strands of clay are produced by way of pressing, from which the hollow and all around closed bricks are cut. The hollow strand is closed at intervals by interior plugs, and in this condition it is severed in the centre of these plugs. The hitherto known devices have however not been satisfactory in use and the desired operation could not be properly carried out therewith. The main reason for this is that the plastic material, for instance the clay, when leaving the outlet of the hollow core of the mouth piece could not easily and accurately be severed from the remaining mass within the hollow core which also caused a deformation of the hollow strand.

By means of the present invention the aforementioned disadvantages are avoided by severing the various plugs within the interior of the hollow strand shaped product at intervals by the action of compressed air or atmospheric air, which is admitted to the inner outlet end of the hollow core of the sleeve.

The further development of the new invention consists also in constructionally perfecting the mechanical mouth piece, namely, its regulating slide in conjunction with the cooperating parts of the apparatus.

Upon the accompanying drawing two methods of construction of the apparatus for carrying out the invention are illustrated and it is:

Fig. 1 a view of the mouth piece according to the invention composed of two parts, the front part of which is turned into the open position through an angle of 180°, so that the interior of the mouth parts becomes visible.

Fig. 2 a vertical section along the line II—II of Figs. 1 and 3 respectively through the closed mouth piece,

Fig. 3 a horizontal section along the line III—III of Fig. 1 through the same mouth piece, while

Fig. 4 shows a modified form of construction for carrying out the invention.

The new mouth piece of the strand press which latter is well known in the brick making industry and therefore not shown on the drawing, and which serves to produce all around closed hollow articles of any desired plastic material such as for instance hollow bricks from clay, consists of the two parts 1 and 2 of which part 1 is rigidly

attached to the strand press, while the second part 2 can be turned into the opened position (see Fig. 1) through an angle of 180° about the shaft 4, which is resting in bearings 3. The opening of the front part 2 enables the exchange of the inner hollow core 5 which is known in itself. This core is provided with bearing ribs 6 (Fig. 1) which in the known manner fit into grooves 6' on the respective inner wall of the front part 2 of the mouth piece. In this way it is possible to insert into the mechanical mouth piece two or more cores instead of one core, and these may be of varying shape and either hollow or solid.

Every hollow core 5 is on the outer surface at least two places opposite to each other (see Fig. 2) double walled so that an intermediate space 7 between these double walls is produced. The interior wall 5' of the hollow core 5 is corrugated and the intermediate space 7 open in the vertical plane at 8' of the outlet 8 of the hollow core 5 in Fig. 2. Through this opening 8' enters the atmospheric air which for instance is admitted by means of two small tubes 9 and which assists in severing the plug which is formed at intervals. The air then flows into the newly formed hollow space and fills it to such an extent that a deforming of the hollow brick by the action of a vacuum is avoided.

These small tubes can of course also be used to admit another external medium such as oxygen gas or a liquid as for instance perfume or another semi-solid or granular material, which is drawn into the hollow space produced in the plastic material or may be forced in by means of pressure as such is for instance done when producing hollow articles of soap.

The admission of the plastic material as for instance brick clay into the hollow core is regulated by means of the turnable slide 13 which in the known manner is attached to a shaft 10 resting in bearings 11 and 12. The effective surface 13' of the slide 13 (Fig. 2) during opening and closing of the hollow core, that is to say when in both end positions, always forms with the direction of the strand of the plastic material leaving the press, a certain acute angle of about 30-60°, in which the inlet opening of the hollow core is arranged eccentrically with regard to the shaft 10 of the slide 13. Consequently the latter is constantly forced by the stream of the plastic material into a position corresponding to one of the two directions of the strand. This is done for the reason of keeping down the initial force required for turning the slide 13. The eccentric position

of the inlet opening of the hollow core is effected by arranging a brake plate 14 in the inlet opening of the hollow core 5. This brake plate 14 in addition thereto serves to simultaneously equalize 5 the speeds of the inner and outer strands of the plastic material.

In order that the plastic material, for instance the brick clay cannot enter the bearings 11 of the shaft 10 arranged on the outer sides of the mouth 10 piece, the inner space of the mouth piece together with the plastic material is separated from the inner bearing 12 by means of a plate 15 (Fig. 3) consisting of metal or of another suitable material.

15 The clear space of the opening of the slide can be adjusted from the outside by fastening to the end of the shaft a lever (not shown) or an adjustable rod which is connected to a movable mechanism, for instance to an automatic device 20 for severing the bricks or to another device for cutting off the objects formed of the plastic material.

The slide 13, 13', shown in Fig. 2, is mounted 25 with its shaft 10 opposite to the inlet opening 16 of the hollow core 5 in such a manner that it stands in front of this shaft 10 with its effective face 13' turned towards the moving direction 25 of the strand.

In order to obtain a still better equalizing of the 30 pressure not only within the hollow core but also outside thereof as well as an increase of the space within the hollow core, this hollow core 5 is at its rear end fitted with a hollow projection 17 35 (Fig. 4), which towards the rear is enlarged conically in the direction of the strand in such a manner that the inlet opening 18 of this projection is much larger than the inlet opening 16 (Figs. 1 and 2) of the hollow core 5, described in the foregoing. In this case however the slide 40 19 is arranged with its effective surface 19' in the front chamber of the described projection 17 in the rear of the turnable shaft 21 of the slide 19, 19'. The material to be worked is effectively 45 compressed by the inclined surface of the projection 17. This kind of hollow core with a front chamber is particularly suitable for mouth pieces of larger dimensions for producing large bricks. The slide plate 19' may be constructed in the way 50 of a Venetian blind so that the size of its effective closing surface can be regulated also by directly adjusting its parts.

I claim as my invention:

1. In an extrusion press mouth piece for producing hollow bodies from plastic material, means 55 for producing a hollow strand of plastic material, means for producing plugs, a hollow core for inserting said plugs at predetermined intervals into said hollow-strand and means for introducing a fluid medium to the periphery of the outlet end 60 of said core to assist in severing the individual plugs from the mass of plastic material in said hollow core.

2. In an extrusion press mouth piece for producing hollow bodies from plastic material, means 65 for producing a hollow strand of plastic material, a hollow core for inserting plugs into said strand at predetermined intervals, said hollow core being closed on the inlet end by a rotatable shutter, the inlet opening of said hollow core being arranged to be offset with respect to the longitudinal axis of the mouth piece in such a manner that the chord of the arcuate surface of 70 said oscillatable core shutter makes an angle of from 30-60° with the said axis in both end or limiting positions of the shutter.

3. In an extrusion press mouth piece by means of which alternately a hollow and a solid strand are formed of plastic material, a hollow core positioned in said mouth piece, a rotatable shutter for opening and closing the inlet end of said hollow core to control the alternate intervals during which said strand is made hollow and solid, a shaft for said shutter, the inlet opening of said hollow core being offset with respect to the longitudinal axis of the mouth piece in such a manner that the chord of the arcuate surface of the oscillatable core shutter makes an angle of from 30-60° with the said axis in both end or limiting positions of the shutter, said shutter being disposed with its effective surface in the rear of the 15 said shutter shaft in the direction of the movement of the strand for the purpose of overcoming the initial resistance to movement of the shutter.

4. In an extrusion press mouth piece by means of which alternately a hollow and a solid strand are formed of plastic material, a hollow core positioned in said mouth piece, a rotatable shutter for opening and closing the inlet end of said hollow core to control the alternate intervals during which said strand is made hollow and solid, a shaft for said shutter, said hollow core being offset with respect to the longitudinal axis of the mouth piece in such a manner that the chord of the arcuate surface of said rotatable core shutter is disposed at an angle of from 30-60° with the said axis in both end or limiting positions of the shutter, said shutter being arranged within a chamber which is widened towards the inlet end, the effective surface of the shutter being disposed in advance of said shutter shaft in the direction of the pressing strand, whereby the inlet opening is enlarged and undue pressure of the shutter upon the plastic material avoided.

5. In an extrusion press mouth piece by means of which alternately a hollow and a solid strand are formed of plastic material, a hollow core positioned in said mouth piece, a rotatable shutter for opening and closing the inlet of said hollow core to control the alternate intervals during which said strand is made hollow and solid, a shaft for said shutter, the inlet opening of said hollow core being offset with respect to the longitudinal axis of the mouth piece in such a manner that the chord of the arcuate surface of said rotatable core shutter is disposed at an angle of from 30-60° with the said axis in both end or limiting positions of the shutter, a plate for partly covering the inlet to said hollow core for the purpose of balancing the speeds of the strands of the plastic material passing around the outside of said hollow core and through said hollow core, said cover plate also forming a shield for the shutter.

6. In an extrusion press mouth piece by means of which alternately a hollow and a solid strand are formed of plastic material, a hollow core positioned in said mouth piece, an arcuate rotatable shutter positioned in said mouth piece the inlet opening of said hollow core being offset with respect to the longitudinal axis of the mouth piece in such a manner that the chord of the arcuate surface of said rotatable core shutter is disposed at an angle of from 30-60° with said axis in both end or limiting positions of said shutter, means for adjusting the degree of opening to the hollow core afforded by the shutter for the purpose of synchronizing the movement of the strands of the plastic material inside and outside of said hollow core.

7. In an extrusion press mouth piece by means of which alternately a hollow and a solid strand are formed of plastic material, a hollow core positioned in said mouth piece, an arcuate rotatable shutter in said hollow core, the inlet opening of said hollow core being offset with respect to the longitudinal axis of said mouth piece in such a manner that the chord of the arcuate surface of the oscillatable core shutter makes an angle of 10 from 30-60° with the said axis in both end or limiting positions of said shutter, a shaft for said shutter, bearings for said shaft arranged at the sides of the mouth piece and cover plates for separating the inner faces of said bearings from 15 the interior of said mouth.

8. In an extrusion press mouth piece for pro-

ducing bodies from plastic material, means for feeding a strand of plastic material to the mouth piece, a hollow core positioned in said mouth piece for forming said strand of elastic material into a hollow tubular strand, means for feeding plastic material into said hollow core for forming plug elements for inserting said plug elements into said hollow tubular strand at predetermined intervals, ducts formed around at least a portion of the periphery of said hollow core, and means for 10 feeding a fluid medium into said ducts to assist in cutting said plug elements of correct length after said plug elements are inserted into said hollow strand. 5
